(57) **CLAIM**

The ornamental design for a pet training clicker, as shown and described.

DESCRIPTION

FIG. 1 is a front, right and top perspective view of a pet training clicker, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front, right and top perspective view of a second embodiment of a pet training clicker.

FIG. 9 is a front elevation view of the second embodiment of the pet training clicker of FIG. 8.

FIG. 10 is a rear elevation view of the second embodiment of the pet training clicker of FIG. 8.

FIG. 11 is a left side elevation view of the second embodiment of the pet training clicker of FIG. 8.

FIG. 12 is a right side elevation view of the second embodiment of the pet training clicker of FIG. 8.

FIG. 13 is a top plan elevation view of the second embodiment of the pet training clicker of FIG. 8; and,

FIG. 14 is a bottom plan elevation view of the second embodiment of the pet training clicker of FIG. 8.

The broken lines shown in the drawings are included for the purpose of illustrating portions of the pet training clicker that form no part of the claimed design.
